UNITED STATES PATENT OFFICE.

RICHARD T. McGEE, OF WHEELING, WEST VIRGINIA.

DIE-CASTING MACHINE.

1,360,771.

Specification of Letters Patent. Patented Nov. 30, 1920.

Application filed March 10, 1920. Serial No. 364,782.

To all whom it may concern:

Be it known that I, RICHARD T. McGEE, a citizen of the United States of America, and resident of Wheeling, county of Ohio, and 5 State of West Virginia, have invented certain new and useful Improvements in Die-Casting Machines, of which the following is a specification.

This invention relates broadly to metal 10 casting apparatus, and more particularly to a mechanism for producing small castings of aluminum and other metals.

The primary object of the invention is to provide an apparatus for casting the metal 15 slugs employed in the production of collapsible tubes, the caps for such tubes and the like.

A further object is to provide a continuously operating machine or apparatus where- 20 by castings of the character mentioned may be rapidly produced in an efficient and wholly automatic manner.

With these and other objects in view, the invention resides in the features of con- 25 struction, arrangement of parts and combinations of elements which will hereinafter be fully described, reference being had to the accompanying drawings, in which—

Figure 1 is a top plan view, partially in 30 broken section, illustrating the invention;

Fig. 2 is a sectional elevation;

Fig. 3 is an enlarged vertical section of a mold;

Fig. 4 is a section on line 4—4, Fig. 3;

Fig. 5 is an enlarged section on line 5—5, 35 Fig. 2, showing the collars on the column;

Fig. 6 is a side elevation of said collars;

Fig. 7 is an enlarged elevation of the os- 40 cillating arm and its mounting; and—

Fig. 8 is an enlarged detail view of a splined pinion, partly in broken section.

Referring to said drawings, in which like designating characters distinguish like parts throughout the several views—

1 indicates generally a furnace of the character disclosed in my co-pending application, Serial No. 331,002, for patent for mold charging device, and 2 the diaphragm-depressing plunger which operates in the 45 fluid-metal receptacle of said device for ejecting the molten metal to and through a conducting tube 3. Said tube leads upward and then laterally through the interior of a heating chamber 4 formed within a casing 50 located at a suitable point upon the furnace 1.

Located adjacent to the furnace 1 in position to successively present to the discharge end of the tube 3 a plurality of molds is the apparatus which constitutes the main part 60 of the present invention. Said apparatus comprises an upright hollow support or column 41 preferably mounted upon a truck 7. Carried rigidly by said column is a supporting flange 8, and rotatably mounted on said 65 flange, as on ball bearings 9 traveling in suitable ball races, is the hub portion 10 of a rotary spider-like table which includes a plurality of radial arms 11 disposed at equi-distant intervals. Each of said arms has 70 formed on its outer end a vertically disposed sleeve-bearing 12 through which is vertically movable a plunger 13 that has its lower end pivotally mounted upon the outer end of a rocker arm 14. The opposite end 75 of said rocker arm 14 is pivotally attached to a guide-block 15 which is vertically movable within a socket 16 provided in a vertically disposed boxing 17 formed integral with the hub 10 of the table. Resting upon 80 said guide-block 15 is the lower end of a coil compression spring 18 which has its upper end seated at the upper end of said socket and which is designed to normally maintain said block in its lowermost position. Said arm 14 carries intermediate its 85 ends a supporting roller 19 which is disposed for travel upon a circular trackway 20 that is suitably supported in a stationary position encircling the support 41.

Rising from each arm 11 adjacent to the outer end thereof is an upright standard 21 which carries a laterally extending horizontal ring 22. Said ring, which occupies a position overhanging the sleeve-bearing 12 95 with its central opening in vertical alignment with the plunger 13, has mounted thereon a head-piece 23 provided with an axial bore 24. Said head-piece is detachably secured to said ring, as by means of 100 screws 25.

The upper end of the plunger 13 has a tapered socket 34 adapted to have mounted therein the correspondingly shaped shank 26 of a lower mold or die 27 which has 105 formed in its upper face a shallow depression or cavity 28 having a contour corresponding to that which shall be possessed by the under side of the casting to be formed. Said cavity registers with and is complementary to a cavity 29 provided in the under 110 face of the head-piece 23 which constitutes

the top mold section or die and which coöperates with the lower mold section or die 27 for giving form to the casting. As depicted in Fig. 3 of the drawings, the dies are designed for casting screw-caps for collapsible tubes, but it is obvious that said dies may have their coöperating faces otherwise shaped for producing other forms of castings.

- 10 When the ring 22 with the attached mold section 23 occupies the position shown at the left side in Fig. 2, the bore 24 of said section directly underlies the vertically disposed discharge end of the metal-conducting tube 3, so that metal ejected from said tube is received within said bore. Immediately following rotary movement of the spider-like table to a point where said mold sections have been withdrawn from underlying relation to the mouth of the casing 5, a plunger 30 is actuated to descend over the upper mold section 23 and to project into the bore 24 a close-fitting removable die 31 having a reduced threaded end 31^a. Displacement of 25 the introduced charge of molten metal is effected by the seating of said die 31 within said bore 24, to the extent that said metal is caused to fill the cavities 28 and 29 and the interstices thereof for producing the desired 30 form of casting.

The die 31 has a tapered shank 32 which is mounted in a tapered socket 33 provided in the end of the plunger 30. Transverse slots 33^a and 34^a are respectively provided in 35 the plungers 30 and 13 in open communication with the sockets 33 and 34. Tail pieces 26^a and 32^a formed on the inner ends of the shanks 26 and 32 extend short distances into said slots 34^a and 33^a, respectively, and are 40 adapted to be abutted by a drift pin or other suitable instrument introduced in said slots for dislodging said shanks from their seats, as when it is desired to substitute other dies.

The plunger 30 operates through a vertical divided sleeve-bearing 35 which is disposed in vertically alined relation to the sleeve-bearing 12 and which is preferably carried by the standard 21. The upper end of said plunger has pivotally attached there- 45 to the outer end of a rocker-arm 36 which is similar in form to the rocker-arm 14 hereinbefore described. The opposite end of said rocker-arm 36 is pivotally connected to a guide-block 37 which is vertically movable 50 within a socket 38 provided in a cylindrical boxing 39 carried by a vertical sleeve 40 which is rotatable upon the upright tubular column 41. Said guide-block 37 rests upon the upper end of a coil compression spring 42 55 which is seated within the socket 38. A roller 43 is carried intermediate the ends of the rocker-arm 36 in underlying relation to a semi-circular trackway 44 which is rigidly carried by supporting arms 62 fixed upon 60 the upper end of the column 41. A retrac- 65

tile coil spring or springs 45 are disposed to normally hold the outer end of the rocker-arm 36 and, consequently, the plunger 30 in elevated position, said spring being suspended at its upper end from a suitable 70 bracket, as 46, and having its lower end attached to said rocker-arm, as shown.

The column 41 is stationary, having its lower end suitably mounted on the truck 7. Fixed upon said column, as by means of set- 75 screws 47, is a collar 48, and underlying said collar is a second collar 49 which rests upon the upper face of the table-hub 10. Provided in appropriate positions in the under face of said collar 49 are two channels 50 80 and 51 of suitable length, each of which is in the form of the arc of a circle struck from the axial center of the collar. Set-screws 52 carried by the collar 48 are directed downward and have their points disposed in seats 85 provided therefor in the upper face of the collar 49, the same being designed for adjustment to form a close-fitting joint between the collar 49 and the hub 10. The object had in view in the provision of said 90 channels 50 and 51 will hereinafter be explained.

In the present embodiment of the invention, the table has eight radial arms 11 and is consequently rotated in each intermittent 95 movement thereof throughout a distance corresponding to one-eighth of a revolution, thus successively presenting the various molds carried by the table in initial or charge-receiving position with respect to 100 the mouth of the charging tube 3. Each of the plungers 13 occupies its extreme elevated position when the charge-receiving position is assumed, due to the fact that the roller 19, which constitutes a fulcrum for the rocker- 105 arm 14, is then positioned on the most elevated portion of the trackway 20. At the same time the plunger 30 occupies its extreme elevated position in which the die 31 carried thereby is withdrawn to a point 110 where it will not interfere with rotation past the charging tube. Said plunger is actuated by the spring 45 to assume its said elevated position, this being permitted because of the absence of any part of the track- 115 way 44 upon that side of the machine.

Promptly following the charging operation the table is advanced one-eighth of a revolution, and during the advance movement the plunger 30 is lowered to the position in which the die 31 carried thereby is seated in the bore of the underlying upper mold section 23 for displacing the metal of the charge, as hereinbefore explained, said plunger being actuated by the travel of the 120 adjacent roller 43 beneath the inclined rear end of the trackway 44, which gradually forces the outer end of the rocker-arm 36 downward against the tension of the attached spring 45. This lowered position of 125 130

the plunger 30 is maintained throughout a suitable portion of the revolution of the table, or until a sufficient interval of time has elapsed to allow the metal of the casting 5 to solidify, as to the third station following that at which the mold was charged, as aforesaid.

Fixed upon the column 41 below the position of the sleeve 40 is a collar 53 having 10 arms 54 which support upon their outer ends a rack-segment 55 which extends throughout a suitable distance, as from the third to the fourth mold station. Said rack-segment is positioned to be engaged by a 15 small pinion 56 fixed upon a vertical shaft 57 which is journaled in bearings 58 and 59 formed, respectively, in the upper end of the standard 21 and in a radial arm 60 which connects the upper end of the sleeve-bearing 20 35 to the adjacent boxing 39. Fixed on said shaft 57 above said pinion 58 is a gear 66 that lies in mesh with a gear or pinion 61 which is loosely splined on the plunger 30 and projects outward through the division 25 formed in the sleeve-bearing 35. As pinion 56 is rotated following its engagement with the rack-segment 55, rearward or reverse rotation is obviously communicated to the plunger 30 and the die 31 for disengaging 30 the threaded end 31^a of the latter from the formed casting.

Shortly prior to the disengagement of the die 31 from the casting, effected as aforesaid, the lower plunger 13 is lowered for 35 withdrawing the lower mold section 27 away from the upper mold section 23. A spout, as 63, is suitably mounted in a stationary position upon an upright support 64 and is located in a position in which it 40 directly underlies the formed casting when the latter is released by the die 31. Said spout is designed to receive the released casting as it falls and to direct the same outward to a suitably located receptacle (not 45 shown). When disengaged from the die 31 the castings will ordinarily adhere to section 23, and means must therefore be provided for dislodging the casting. To accomplish this air is directed downward 50 through the bore 24 of said section 23 with sufficient force to dislodge such castings. Said air-directing means comprises an air-conducting pipe 62 leading from a source of supply (not shown) to a suitable nozzle 55 65 which overhangs said spout and between which and said spout the upper mold section moves immediately following the elevation of said plunger 30 and die 31, which elevation occurs instantly following the disengagement of said die. At the proper moment—that is, when the bore 24 directly 60 underlies the downturned mouth of the nozzle 65—a blast of air is directed downward from the nozzle, said blast being released by 65 the opening of a valve 67 of pop-valve type

located at a suitable point in the pipe 62. Said valve is opened at proper intervals by engagement with a pivoted valve-stem-depressing lever 68 carried by the valve casing, of an arm 69, carried by an oscillating 70 supporting element 70.

Said element 70 is of approximately L shape and has the end of its horizontal member pivotally mounted upon a vertically disposed spindle 71 fixed centrally on the under side of the frame of the truck 7. Connected to the upright member of said element 70 through the intermediacy of a suitable joint 72 of universal type is one end of a connecting-rod 73 through which oscillatory movement is communicated to the table for effecting intermittent, or step-by-step, rotation of the latter. The opposite end of said connecting-rod is in like manner connected to a wrist-pin 74 carried by a 85 wheel or disk 75 to which motion is communicated from a belt-driven shaft 76 through suitable gearing, which gearing, as herein illustrated, is also utilized to actuate means for opening and closing the valves 90 by which the flow of metal to and from the receptacle of the mold-charging device of the co-pending application hereinbefore referred to is controlled. Further, said gearing is employed to actuate a lever 77 by 95 which the diaphragm-depressing plunger 2 of said device is lowered at the proper times. As herein shown, said gearing comprises a sprocket wheel 78 fixed on the shaft 76 and connected by a sprocket chain 79 to a 100 sprocket wheel 80 fixed on the shaft 81 which carries the disk 75.

Pivoted upon the upper end of the upright member of the L-shaped element 70 is a spring-pressed latch 82 which at the 105 extreme limit of the outward thrust of the connecting-rod 73 assumes interlocking engagement with the outer end of one of the arms 11 of the rotary spider-like table and by which said table is actuated to rotate 110 throughout one-eighth of a revolution during the return movement of said connecting-rod. At the completion of the rotary movement aforesaid a spring-pressed latch 83 mounted upon a suitable stationary support, 115 as a standard 84 carried by the truck, interlocks with an arm 11 of the table, as by engagement of its point with a recess or seat 85 provided therefor in said arm, for maintaining the table stationary during the 120 interval preceding the next succeeding advance movement of the table.

Leading through the interior of the column 41 to a point above the position occupied by the collar 48 are two pipes 86 and 87, the former being an air-conducting pipe and the latter a gas-conducting pipe. Said pipes lead outward through opposite sides of said column, thence downward through relatively large openings 88 provided there- 130

for in said collar and have their ends rigidly mounted in the collar 49. The air-conducting pipe 86 opens into the arcuately curved groove or channel 50 provided in the under 5 face of said collar 49 adjacent to the inner peripheral edge of the latter, and the gas-conducting pipe 87 opens into the arcuate groove or channel 51 provided in the under face of said collar adjacent to the outer peripheral edge of the latter. In the rotation, 10 of the table the ends of air pipes 90 which open upward through the top face of the hub 10 are successively moved into open communication with said channel 50. Said pipes 90 lead outward from said hub along each of the table-arms 11 and carry blast nozzles 91 upon their outer ends adjacent to the upper ends of the sleeve-bearings 12 carried by said arms. Likewise, in the rotation 15 of the table the ends of gas pipes 92 which open upward through the top face of the hub 10 are successively moved into open communication with the channel 51. Said pipes 92 lead outward along the arms 11 and 20 carry suitable burner nozzles, as 93, adjacent to the upper ends of said sleeve-bearings 12. Said channels 50 and 51 are located at opposite sides of the collar 49, as 25 indicated in dotted lines in Fig. 5.

30 Immediately following the dislodgment of a formed casting from a mold, the pipe 92 leading along the arm which carries said mold comes into open communication with the outer end of the gas channel 51, and gas 35 is admitted therethrough to the burner nozzle 93 thereof. The gas which then starts to issue from said burner is immediately ignited by flame from a suitably located constantly-burning pilot light, as 94. This 40 burner is maintained lighted during the interval in which the mold associated therewith is being advanced to charge-receiving position, and in said interval directs flame against said mold whereby the latter is 45 heated to a high temperature. With the initial advance movement of the mold after being charged, the inner end of the pipe 92 through which gas is supplied to the burner 93 which is associated therewith passes out 50 of communication with the channel 51 and cuts off the supply of gas to said burner. Promptly following the cutting off of the gas supply, as aforesaid, the air pipe 90 leading along the arm which carries the 55 mold which has just been charged comes into open communication with the adjacent end of the air channel 50, and air is admitted therethrough and issues from the nozzle 91 thereof in the form of a blast 60 which plays upon said mold for rapidly cooling the latter and the formed charge. The air continues to play upon said mold until, at a point adjacent to the casting-ejecting point, said pipe 90 passes out of

communication with said channel 50, cutting off the air supply to said nozzle.

To facilitate the rapid heating and cooling of the mold, effected as described, a plurality of vertical openings or perforations 95 are provided in the mold section 23 in 70 encircling relation to and at a suitably spaced distance from the bore 24 of said mold section, said perforations being adapted to admit of the passage of flame from the burners for heating purposes and the passage of air for cooling purposes. 75

What is claimed is—

1. The combination with means for delivering charges of molten metal, of an automatic casting-producing apparatus comprising a rotary support, a plurality of radially disposed members carried by said support, molds carried by said members, means whereby intermittent rotary movement is imparted to said support for successively positioning said molds with respect to said delivery means, reciprocating means for forcing the metal of the introduced charges throughout the mold cavities to give form to the castings, said means being automatically actuated by rotation of said support and remaining in operative position during a portion of the travel of said molds, means for pre-heating the molds, and means for artificially cooling said molds and the metal of the castings following the forming operation. 90

2. The combination with means for delivering charges of molten metal, of an automatic casting-producing apparatus comprising a rotary support, a plurality of radially disposed members carried by said support, molds carried by said members, means whereby intermittent rotary movement is imparted to said support for successively 100 positioning said molds with respect to said delivery means, means reciprocable with respect to said molds to compress the metal of the introduced charges throughout the mold cavities for giving form to the castings, 110 said means continuing in compressing position throughout a part of the rotation of said support, means for pre-heating said molds, and means for artificially cooling said molds and the metal of the shaped castings following the forming operation and 115 prior to withdrawal of said compressing means.

3. The combination with means for delivering charges of molten metal, of an automatic casting-producing apparatus comprising a rotary column, a plurality of radially disposed members carried by said column, molds carried by said members, means whereby intermittent rotary movement is 120 imparted to said column for successively positioning said molds with respect to said delivery means, means movable into said molds 125

for compressing the introduced charges throughout the mold cavities to give form to the castings, means for preheating said molds, means for artificially cooling said 5 molds and the contained castings, said cooling means acting throughout a predetermined interval following the forming operation, and rotary means for withdrawing said compressing means near the end of the 10 cooling interval.

4. The combination with means for periodically delivering charges of molten metal, of an automatic casting-producing apparatus comprising a rotary support, a 15 plurality of molds carried by said support, means whereby intermittent rotary movement is imparted to said support for successively positioning said molds with respect to said delivery means, means operating 20 to compress the metal of the introduced charges throughout the mold cavities for giving form to the castings, said compressing means being adapted to remain in operative position throughout a predetermined 25 interval, means for artificially cooling said molds and the contained castings following the compressing operation, and rotary means for withdrawing said compressing means following a cooling interval.

30 5. The combination with means for periodically delivering charges of molten metal, of an automatic casting-producing apparatus comprising a rotary support, a plurality of molds carried by said support, 35 means whereby intermittent rotary movement is imparted to said support for successively positioning said molds with respect to said delivery means, means operating to compress the metal of the introduced charges 40 throughout the mold cavities for giving form to the castings, said compressing means being adapted to remain in operative position throughout a predetermined portion of the rotation, means for artificially cooling 45 said molds and the contained castings following the compressing operation, rotary means operating during rotation of said support and following a cooling interval whereby said compressing means is detached from the castings, and means for dislodging the castings from the molds.

6. The combination with means for periodically delivering charges of molten metal, of an automatic casting-producing apparatus 55 comprising a rotary support, a plurality of molds carried by said support, means whereby intermittent rotary movement is imparted to said support for successively positioning said molds with respect to said delivery means, means operating to compress the metal of the introduced charges throughout the mold cavities for giving form to the castings, said compressing means being adapted to remain in operative position 60 throughout a predetermined interval, means

for artificially cooling said molds and the contained castings following the compressing operation, means for withdrawing said compressing means following a cooling interval, means for opening the molds, and means for 70 dislodging the castings from the molds.

7. The combination with means for periodically delivering charges of molten metal, of an automatic casting-producing apparatus comprising a rotary support, a plurality of molds carried by said support, means whereby intermittent rotary movement is imparted to said support for successively positioning said molds with respect to said delivery means, means for pre-heating said 75 molds, means operating to compress the metal of the introduced charges throughout the mold cavities for giving form to the castings, said compressing means being held in operative position throughout a predetermined portion of the rotation, means for directing blasts of air upon said molds for effecting the rapid cooling of the latter and the contained castings following the compressing operation, means for withdrawing 80 said compressing means following an interval of cooling, and means for opening and closing the molds at predetermined intervals.

8. The combination with means for periodically delivering charges of molten metal, of an apparatus for casting threaded metal caps for collapsible tubes and the like, said apparatus comprising a rotary support, a plurality of sectional molds carried by said support, means for opening and closing the mold sections at predetermined intervals, means whereby intermittent rotary movement is imparted to said support for successively positioning said molds with respect to said delivery means, means movable into said molds to compress the metal of the introduced charges throughout the mold cavities for giving form to the castings, said compressing means having thereon matrix 95 threads upon which the threads of the castings are shaped, means for artificially cooling said molds and the contained castings following the compressing operation, means for rotating said compressing means in a 100 reverse direction for disengaging the same from the cooled casting, and means for withdrawing the disengaged compressing means from the mold.

9. The combination with means for periodically delivering charges of molten metal, of an apparatus for casting threaded metal caps for collapsible tubes and the like, said apparatus comprising a rotary support, a plurality of molds each comprising upper 120 and lower sections carried by said support, the lower sections being movable at predetermined intervals into and out of cooperative relation to the upper sections, the upper section of each mold having a vertical bore 125 130

- therein, means whereby intermittent rotary movement is imparted to said support for successively positioning said molds with the bores thereof in underlying relation to said 5 delivery means, an element vertically movable with respect to each mold and carrying a die which is depressed into the latter through the bore thereof for compressing the metal of the introduced charge to give form 10 to the casting, said die having matrix threads upon which the threads of the casting are shaped, and means for rotating said element for disengaging the threads thereof from those of the casting.
- 15 10. The combination with means for periodically delivering charges of molten metal, of an apparatus for casting threaded metal caps for collapsible tubes and the like, said apparatus comprising a rotary support, a 20 plurality of molds each comprising upper and lower sections carried by said support, the lower sections being movable at predetermined intervals into and out of co-operative relation to the upper sections, the upper 25 section of each mold having a vertical bore therein, means whereby intermittent rotary movement is imparted to said support for successively positioning said molds with the bores thereof in underlying relation to said 30 delivery means, a plunger movable vertically with respect to each mold and carrying a part which enters the bore of the mold for compressing the metal of the introduced charge to give 35 form to the casting, said compressing part having matrix threads upon which the threads of the casting are formed, and means for rotating said plunger to disengage the matrix threads from the casting. 90
11. The combination with means for periodically delivering charges of molten metal, of an apparatus for casting threaded metal caps for collapsible tubes and the like, said apparatus comprising a rotary support, a 40 plurality of molds each comprising upper and lower sections carried by said support, the lower sections being movable at predetermined intervals into and out of co-operative relation to the upper sections, the upper section of each mold having a vertical bore 45 therein, means whereby intermittent rotary movement is imparted to said support for successively positioning said molds with the bores thereof in underlying relation to said 50 delivery means, a plunger movable vertically with respect to each mold and carrying a part which enters the bore of the mold for compressing the metal of the introduced charge to give 55 form to the casting, said compressing part having matrix threads upon which the threads of the casting are formed, means for artificially cooling the mold and the contained casting while the compressing part remains engaged with the casting, and means for producing reverse rotation of said 60 plunger to disengage the matrix threads of said part from the casting. 105
12. The combination with means for periodically delivering charges of molten metal, of an apparatus for casting threaded metal caps for collapsible tubes and the like, said apparatus comprising a rotary support, a 65 plurality of molds each comprising upper and lower sections carried by said support, the lower sections being movable at predetermined intervals into and out of co-operative relation to the upper sections, the upper section of each mold having a vertical bore 70 therein, means whereby intermittent rotary movement is imparted to said support for successively positioning said molds with the bores thereof in underlying relation to said 75 delivery means, means for pre-heating said molds, a plunger movable vertically with respect to each mold and carrying a part which enters the bore of the mold for compressing the metal of the introduced charge to give 80 form to the casting, said compressing part having matrix threads upon which the threads of the casting are formed, and means for rotating said plunger to disengage the matrix threads from the casting. 90
13. The combination with means for periodically delivering charges of molten metal, of an apparatus for casting threaded metal caps for collapsible tubes and the like, said apparatus comprising a rotary support, a 85 plurality of molds each comprising upper and lower sections carried by said support, the lower sections being movable at predetermined intervals into and out of co-operative relation to the upper sections, the upper section of each mold having a vertical bore 95 therein, means whereby intermittent rotary movement is imparted to said support for successively positioning said molds with the bores thereof in underlying relation to said 100 delivery means, means for pre-heating said molds, a plunger movable vertically with respect to each mold and carrying a part which enters the bore of the mold for compressing the metal of the introduced charge to give 105 form to the casting, said compressing part having matrix threads upon which the threads of the casting are formed, means for artificially cooling the mold and the contained casting while the compressing part remains engaged with the casting, and means for producing reverse rotation of said 110 plunger to disengage the matrix threads of said part from the casting. 115
14. The combination with means for periodically delivering charges of molten metal, of an apparatus for casting threaded metal caps for collapsible tubes and the like, said apparatus comprising a rotary support, a 115 plurality of molds each comprising upper and lower sections carried by said support, the lower sections being movable at predetermined intervals into and out of co-operative relation to the upper sections, the upper section of each mold having a vertical bore 120 therein, means whereby intermittent rotary movement is imparted to said support for successively positioning said molds with the bores thereof in underlying relation to said 125 delivery means, means for pre-heating said molds, a plunger movable vertically with respect to each mold and carrying a part which enters the bore of the mold for compressing the metal of the introduced charge to give 130 form to the casting, said compressing part having matrix threads upon which the threads of the casting are formed, means for artificially cooling the mold and the contained casting while the compressing part remains engaged with the casting, and means for producing reverse rotation of said plunger to disengage the matrix threads of said part from the casting. 130

- cal bore therein, means whereby intermittent rotary movement is imparted to said support for successively positioning said molds with the bores thereof in underlying relation 5 to said delivery means, means for pre-heating said molds, a plunger movable vertically with respect to each mold and carrying a part which enters the bore of the mold for compressing the metal of the introduced charge to give form to the casting, said compressing part having matrix threads upon which the threads of the casting are formed, means for artificially cooling the mold and the contained casting while the compressing 10 part remains engaged with the casting, means for producing reverse rotation of said plunger to disengage the matrix threads of said part from the casting and means for withdrawing one of the mold sections from 15 coöperative relation to the other to release the casting.
15. The combination with means for periodically delivering charges of molten metal, of an apparatus for casting threaded metal caps for collapsible tubes and the like, said apparatus comprising a rotary support, a plurality of molds each comprising upper and lower sections carried by said support, the lower sections being movable at predetermined intervals into and out of coöperative relation to the upper sections, the upper section of each mold having a vertical bore therein, means whereby intermittent rotary movement is imparted to said support 30 for successively positioning said molds with the bores thereof in underlying relation to said delivery means, means for pre-heating said molds, a plunger movable vertically with respect to each mold and carrying a part which enters the bore of the mold for compressing the metal of the introduced charge to give form to the casting, said compressing part having matrix threads upon which the threads of the casting are formed, 35 means for artificially cooling the mold and the contained casting while the compressing part remains engaged with the casting, means for producing reverse rotation of said plunger to disengage the matrix threads of said part from the casting, means for withdrawing one of the mold sections from coöperative relation to the other to release the casting, and means for dislodging the released casting.

16. The combination with means for periodically delivering charges of molten metal, of an apparatus for casting threaded metal caps for collapsible tubes and the like, said apparatus comprising a rotary support, a plurality of molds each comprising upper and lower sections carried by said support, the lower sections being movable at predetermined intervals into and out of coöperative relation to the upper sections, the upper section of each mold having a vertical bore therein, means whereby intermittent rotary movement is imparted to said support for successively positioning said molds with the bores thereof in underlying relation to said delivery means, a plunger movable vertically with respect to each mold and carrying a part which enters the bore of the mold for compressing the metal of the introduced charge to give form to the casting, said compressing part having matrix threads upon which the threads of the casting are formed, means for rotating said plunger to disengage the threaded part from the casting, gas-conducting means including passages adapted to be opened and closed at predetermined intervals in the travel of said molds, a gas burner located adjacent to each of said molds, means for igniting gas issuing from said burners, said burners being adapted to direct blasts of flame against said molds for pre-heating the latter, and means for artificially cooling the molds and the contained castings during the interval between the compressing operation and the disengagement of the plunger from the casting.
17. The combination with means for periodically delivering charges of molten metal, of an apparatus for casting threaded metal caps for collapsible tubes and the like, said apparatus comprising a rotary support, a plurality of molds each comprising upper and lower sections carried by said support, the lower sections being movable at predetermined intervals into and out of coöperative relation to the upper sections, the upper section of each mold having a vertical bore therein, means whereby intermittent rotary movement is imparted to said support for successively positioning said molds with the bores thereof in underlying relation to said delivery means, a plunger movable vertically with respect to each mold and carrying a part which enters the bore of the mold for compressing the metal of the introduced charge to give form to the casting, said compressing part having matrix threads upon which the threads of the casting are formed, means for rotating said plunger to disengage the threaded part from the casting, gas-conducting means including passages adapted to be opened and closed at predetermined intervals in the travel of said molds, a gas burner located adjacent to each of said molds, means for igniting gas issuing from said burners, said burners being adapted to direct blasts of flame against said molds for pre-heating the latter, and means for directing cooling blasts of air against the molds during the interval between the compressing operation and the disengagement of the plunger from the casting.
18. The combination with means for periodically delivering charges of molten metal, of an apparatus for casting threaded metal caps for collapsible tubes and the like, said

apparatus comprising a rotary support, a plurality of molds each comprising upper and lower sections carried by said support, the lower sections being movable at predetermined intervals into and out of co-operative relation to the upper sections, the upper section of each mold having a vertical bore therein, means whereby intermittent rotary movement is imparted to said support for 5 successively positioning said molds with the bores thereof in underlying relation to said delivery means, a plunger movable vertically with respect to each mold and carrying a part which enters the bore of the mold for 10 compressing the metal of the introduced charge to give form to the casting, said bore-entering part having matrix threads upon which the threads of the casting are formed, means for rotating said plunger to 15 disengage the threaded part from the casting, gas-conducting means including pas- 20

sages adapted to be opened and closed at predetermined intervals in the travel of said molds, a gas burner located adjacent to each of said molds, means for igniting gas issuing from said burners, said burners being adapted to direct blasts of flame against said molds for pre-heating the latter, and means for directing cooling blasts of air against the molds during the interval between the compressing operation and the disengagement of the plunger from the casting, said cooling means comprising air-conducting passages adapted to be opened and closed at predetermined intervals. 25 30 35
